UNITED STATES PATENT OFFICE.

LOUIS C. GREINER, OF EVANSVILLE, INDIANA.

METHOD OF ATTACHING LINOLEUM.

Application filed July 24, 1924. Serial No. 727,952.

To all whom it may concern:

Be it known that I, LOUIS C. GREINER, residing in the city of Evansville, county of Vanderburg, and State of Indiana, a citizen 5 of the United States, have invented certain new and useful Improvements in Methods of Attaching Linoleum, of which the following is a specification, reference being had to the accompanying drawing, forming a part 10 thereof.

My invention relates to a method of attaching linoleum or other materials of a like nature, to the top of desks or tables or other articles of furniture. Linoleum is used to 15 day in many instances, as a covering for desks or tables because of its sanitary qualities and its adaptability as such coverings, which makes it readily washable without injury to the surface.

20 A further object is to provide a construction or means of applying the linoleum to the sides and ends of the top and obtaining a finished edge where the edges of the linoleum meet each other.

25 Heretofore in the use of linoleum as a covering for tables or desks it has been the policy to merely cover the top and finish the sides and ends with border strips of wood or metal but not with linoleum. In 30 any of these methods commonly used there was no chance to obtain an absolutely water tight joint between the linoleum and the border strips and the space between these two were filled up with glue. This construction was all right in the general run of cases but upon close observation the space filled up with glue could be seen and the appearance therefore was spoiled. In the desk tops having metal border strips the 35 water could run under the edge and eventually get to the wood top thereby subjecting the top to rotting. In the present construction the joints are absolutely waterproof.

40 It is a further object of my invention to provide a top which will have a neat appearance and prove durable, the appearance being that of inlay.

45 With the objects above indicated and other objects hereinafter explained in view, my invention consists in the method as hereinafter set forth and claimed.

50 Referring to the drawings—

55 Figure 1 is a front view of a desk showing the top applied thereto.

Figure 2 is a top plan view of the same top.

Figure 3 is a cross sectional view on line 3—3 of Figure 2 showing the means of attaching the linoleum.

Figure 4 is a fragmentary bottom view 60 showing the locking means in the corner construction.

Figure 5 is a fragmentary perspective view of one corner of the top.

Figure 6 is a fragmentary sectional view 65 taken on line 6—6 of Figure 2 showing the corner locking means.

In the drawings 1 indicates a top made of 5 or 7 ply laminated wood and built up to the desired thickness. 2 indicates the linoleum which is attached by means of a water proof or other high grade glue to the veneer strip or strips 3 which is likewise securely fastened to the upper side of the laminated top 1. The laminated top 1 is provided with a veneered strip or strips 4 securely fastened to the bottom thereof by means of water proof glue or other means. The top is then cut to the proper size and the ends and sides finished off. Linoleum 70 end strips 5 and 6 and side strips 7 and 8 of the proper length and of depth sufficient to extend to the bottom of said top are then securely fastened by means of glue and are allowed to dry. When the glue has entirely 75 dried a special machine is run along the four upper edges and grooves 9 are cut of the desired width and depth and at an angle of about 45°. Locking strips 11, 12, 13 and 14 of wood are then forced into the grooves 80 85 90 95 98 99 100 105 110 115 116 117 118 119 120 121 122 123 124 125 126 127 128 129 130 131 132 133 134 135 136 137 138 finished off so as not to leave any loose place between them, thereby leaving an absolutely water tight joint.

The veneer strips shown may be omitted 5 and the process works just as well but this veneer strip is found in the ordinary construction of wood desk tops.

It will be readily seen from the method described that linoleum or material of like 10 nature may be securely attached to various surfaces without deviating from the spirit of the invention.

It is to be further seen from the construction that the finished article has the 15 appearance of inlay work and will be very economical to construct and much superior to any way in which linoleum or other material is at present attached to any surface.

20 Having thus described my invention what I claim is:

1. The method of making a top for a desk or table which consists in forming a base of relatively hard material with sides 25 at right angles to its upper face, securing to its upper face a covering of flexible material and securing to its sides coverings of similar material, forming grooves along the meeting edges of the sides and upper 30 face extending through the coverings into the base at an angle oblique to the plane of the top, inserting into these grooves strips of relatively hard material and securing them in place and so finishing the 35 upper edges of these strips that their top faces will be in the plane of the upper surface of the top covering and their side edges will be in the plane of the outer surface of the adjacent side covering.

2. The method of making a top for a 40 desk or table which consists in forming a base of relatively hard material with sides at right angles to its upper face, securing to its upper face a covering of flexible material, forming grooves along the meeting 45 edges of the sides and upper face extending through the coverings into the base at an angle oblique to the plane of the top, inserting into these grooves strips of relatively hard material and securing them in 50 place, forming at the meeting edges of adjacent sides recesses extending through the side coverings into the base, inserting into said recesses strips of relatively hard material and securing them in place and so 55 finishing the several strips that their upper edges will be in the plane of the upper face of the top covering and their side edges will be in the planes of the outer surfaces of adjacent side coverings.

3. A desk or table top comprising a base of relatively hard material having sides at right angles to its upper face, a covering of flexible material secured to the upper face of the base, strips of similar material secured to its sides, and edge strips extending along the meeting edges of the sides and upper face extending into the base at an angle oblique to the plane of the upper 60 face and having the upper and side faces 65 of their outer edges in the planes of the upper surface of the top covering and the outer surfaces of the adjacent side covering respectively.

70 In testimony whereof, I hereunto affix my 75 signature.

LOUIS C. GREINER.
